SUPPORTING STRAP FOR ELECTRIC FIXTURES

Robert L. Davison, New York, N. Y., assignor to
 John B. Pierce Foundation, New York, N. Y.,
 a corporation of New York

Application December 22, 1934, Serial No. 758,739

6 Claims. (Cl. 247—21)

My present invention relates to supporting devices, and more particularly to an improved supporting strap for electric light or similar fixtures.

5 My invention is designed to enable an electric fixture to be adjustably supported in position in a ceiling or wall of a building, and without the necessity of having the support rigidly or otherwise secured to the supporting joists or
 10 studding. In carrying out my invention I provide a supporting strap or similar member, usually channel-shaped in cross section, and provided on the bottom of the U with an elongated rectangular slot, and position this strap with the
 15 slot therein in registry with a hole in the wall or ceiling. Associated with the U-shaped strap, and particularly with the elongated rectangular slot therein I provide an outlet fixture, or member, such as a chandelier support, or a socket for an electric connection. One end of such outlet fixture, or member, is of rectangular construction having its larger dimension, or length, less than the length of the rectangular slot in the strap, and greater than the width of such rectangular slot, and a width less than the width
 20 of the rectangular slot. Preferably also, the outlet fixture, or member, is provided with conductors as an integral part thereof, and adapted for attachment with the electric supply system in the house, or other building in which the same is located. On one face of the rectangular member, and extending outwardly therefrom, is a member provided on its interior with threads for receiving a threaded electric member, such as an
 25 electric light bulb, or a screw socket plug, such member is also provided with threads on its outer periphery for engagement with the internal threads of a ceiling plate. The device may be associated with the U-shaped strap, with the rectangular member on one side of the bottom of such strap, and with the connecting end on the other side thereof. Such connecting end extends through the wall or ceiling, and is adapted to be held in adjusted position with relation
 30 to the rectangular slot in the U-shaped strap by the ceiling plate above referred to.

40 The device is adapted for use in new or old building structures. That is, it may be incorporated in the wiring system during the erection of the building, or may be utilized in a wiring system being installed in a building at any time after the completion thereof.

45 In the accompanying drawing illustrating a preferred embodiment of my invention,

55 Fig. 1 is a sectional elevation, of a portion of

a building structure, showing my device in position with respect to the ceiling and between adjacent joists.

Fig. 2 is a top plan view of Fig. 1.

Fig. 3 is an elevation, partly in section, of the 5 U-shaped strap and the connecting member.

Fig. 4 is a view similar to Fig. 3, and showing the connecting device inserted through the rectangular slot in the U-shaped strap.

Fig. 5 is a view, similar to Figs. 3 and 4, showing the connecting member in its final position after having been rotated through an angle of 90°, and

Fig. 6 is a bottom plan view of the central portion of Fig. 1.

Referring to the drawing, 10 designates a supporting strap, substantially U-shaped in cross section, and provided on the central portion of the bottom of the U with an elongated rectangular slot 11. On the under face of the U-shaped supporting member or strap 10, and at each end of the elongated rectangular slot 11 are downwardly extending members 12. The U-shaped strap 10 is adapted to be positioned between adjacent joists 13 supporting a ceiling, or between equivalent members, such as the studding in a wall. Secured to the under faces of the joist 13 is the usual ceiling, comprised, say of, laths 14 and plaster 15, together with the finish coat 16. At the designated point in a room, of which the ceiling referred to forms a part, the portion of a light fixture, such as a chandelier or other fixture, is determined upon, and thereupon a hole 17 is made in the ceiling through the plaster 15 and lath 14 as indicated in Fig. 1. The hole 17 is generally 30 round, and of a diameter slightly greater than the distance between the downwardly extending members 12 on the U-shaped supporting strap 10. The members 12 act therefore, as a means for accurately positioning the U-shaped strap 10 with 35 respect to the hole 17.

Associated with the U-shaped strap 10 is a connecting member comprised of a rectangular portion 18, of a length less than the length of the elongated rectangular slot in the U-shaped strap 40 45 10, and greater than the width of such slot 11. The rectangular element 18 acts as a housing for electric connections (not shown) and which have connected thereto the conductors 19 and 20 contained in the cable 21. A removable cover 22 for the rectangular element 18 provides access to the electric connectors above referred to. On the face of the rectangular element 18, remote from the cover plate 22, is formed integral therewith and extending downwardly therefrom, a cylindrical 50 55

member 23, provided at its lower free end with internal threads 24a for the purpose of allowing a chandelier or other lighting fixture to be screwed therein in the usual manner. Also, this cylindrical member 23 is provided at its lower free end with external threads 24. The length of the member 23 is such that when the rectangular element 18 is correctly positioned in the U-shaped strap 10, with respect to the elongated slot 11 therein, the stated lower end bearing the internal threads 24a and the external threads 24 will extend downward to a point below the face of the ceiling above referred to. Associated with the external threads 24 is a ceiling plate 25, and which acts to hold the connecting member in adjusted position with respect to the slot 11 and the supporting strap 10.

When assembling the various elements above referred to, the substantially circular hole 17 is formed in the ceiling and in the supporting laths 14. The U-shaped supporting strap 10 is then placed in position as shown in Fig. 1, and in the case where the device is to be secured to a ceiling the downwardly extending members 12 extend into the hole 17, as shown in Fig. 1. The rectangular member 18 with the integrally formed cylindrical member 23, together with the cable 21 is then associated with the elongated slot 11.

This may be done by passing the cable 21 through the elongated slot 11 from the bottom of the ceiling upwardly into the space between the joists 13, the cable 21 being followed by the rectangular member or element 18. This upward movement is continued until the cable 21 and rectangular element 18 occupy the dot-and-dash position shown in Fig. 3. This "threading" movement of the rectangular element 18 through the elongated slot 11 is permitted because of the fact that the width of the rectangular element 18 is less than the width of the elongated rectangular slot 11. Upon reaching the position shown in Fig. 3 or Fig. 4, the rectangular element 18 is rotated through an angle of 90°, assuming the position shown in Fig. 5, where it will be noted that because of the fact that the length of the rectangular element 18 is greater than the width of the elongated slot 11, such rectangular member 18 cannot be then passed through the rectangular slot 11. Also because of the fact that the width of the rectangular element 18 is considerably less than the elongated slot 11, there is permitted a considerable range of movement of the rectangular element 18, together with the cylindrical member 23, along the length of the slot 11. This allows for adjustment, and therefore the rectangular member or element 18 is moved backward or forward along the slot 11 until in proper position, whereupon the internally threaded ceiling plate 25 is screwed onto the external threads 24 and the rectangular element 18 is firmly secured in adjusted position.

Where the device is to be installed in a building already completed, the rectangular plate 10 is passed through the hole 17 and into the position shown in Fig. 1. The cable 21 is then "fished" through the rectangular hole 11 in the plate 10 to a point below the ceiling 15, or wall. The cover plate 22 is then removed from the rectangular block 18, the ends of the wires 19 and 20 connected to the terminals within such rectangular block 18, and the cover plate 22 replaced. The rectangular block 18 is then passed upwardly through the rectangular hole 11 and adjustably positioned as above described.

75. My improved device is as readily removed from

the position shown as it was originally inserted therein. It will however, be firmly retained in adjusted position until the ceiling plate 25 is partially unscrewed from the threads 24.

It is to be understood that the embodiment of the invention herein described and illustrated is merely a convenient and useful form of the invention, which is capable of other modifications without departing from the spirit and scope of the invention as defined in the appended claims. 10

I claim.

1. In a supporting device, an elongated strap provided with an elongated slot of predetermined width and length, a rectangular member having a width less than the width of said slot and a length greater than the width of said slot, to permit said member to be inserted through said elongated slot and thereafter rotated to position its greater length across the width of the slot a member depending from the rectangular member, and a clamping member engaging with the depending member, for clamping the rectangular member in adjusted position relative to the length of said slot. 15

2. In a supporting device, an elongated strap provided with an elongated slot of predetermined width and length, a rectangular member having a width less than the width of said slot and a length greater than the width of said slot, to permit said member to be inserted through said elongated slot and thereafter rotated to position its greater length across the width of the slot a member formed integral with and depending from the rectangular member, and a clamping member engaging with the depending member, 20 for clamping the rectangular member in adjusted position relative to the length of the said slot. 25

3. In a supporting device, an elongated strap provided with an elongated slot of predetermined width and length, a rectangular member having a width less than the width of said slot and a length greater than the width of said slot, to permit said member to be inserted through said elongated slot and thereafter rotated to position its greater length across the width of the slot a cylindrical member formed integral with and depending from the rectangular member, and a clamping member engaging with the depending member, 45 for clamping the rectangular member in adjusted position relative to the length of the said slot. 50

4. In a supporting device, an elongated strap provided with an elongated slot of predetermined width and length, a rectangular member having a width less than the width of said slot and a length greater than the width of said slot, to permit said member to be inserted through said elongated slot and thereafter rotated to position its greater length across the width of the slot a cylindrical member formed integral with and depending from the rectangular member, and a threaded clamping member engaging with the depending member, for clamping the rectangular member in adjusted position relative to the length of the said slot. 55

65. 5. In a supporting device, an elongated U-shaped strap provided with an elongated rectangular slot in its bottom portion, a rectangular block member having a width less than the width of the said slot and a length greater than the width of the said slot, to permit said member to be inserted through said rectangular slot and thereafter rotated to position its greater length across the width of the slot a cylindrical member formed integral with and depending from, 70

75.

the rectangular block member and provided with external threads at its lower end, and an internally threaded clamping member engaging with the threads on the depending member, for clamping the rectangular block member in adjusted position relative to the length of the said slot. 5

6. In a supporting device, an elongated U-shaped strap provided with an elongated rectangular slot in its bottom portion, a rectangular block member having a width less than the width of said slot and a length greater than the width of said slot, to permit said member to be inserted 10

through said elongated rectangular slot and thereafter rotated in position its greater length across the width of the slot a cylindrical member formed integral with and depending from the rectangular block member and provided with external threads at its lower end, and an internally threaded clamping member engaging with the threads on the depending member, for clamping the rectangular block member in adjusted position relative to the length of the said slot. 10
